(57) CLAIM

The ornamental design for a printer, as shown and described.

DESCRIPTION

FIG. 1 is a top, front, left side perspective view of a printer showing my new design;

FIG. 2 is a top front, left side perspective view thereof with paper trays extended;

FIG. 3 is a top plan view thereof;

FIG. 4 is a front elevational view thereof;

FIG. 5 is a rear elevational view thereof;

FIG. 6 is a left side elevational view thereof; and,

FIG. 7 is a right side elevational view thereof.

The bottom of this printer normally rests on a surface and is not seen nor intended to be seen as a part of my new design.

1 Claim, 6 Drawing Sheets
